UNITED STATES PATENT OFFICE.

WILLIAM G. TEMPLETON, OF COLORADO SPRINGS, COLORADO, ASSIGNOR
OF TWO-THIRDS TO W. J. BRASFIELD AND W. T. ADAIR, OF ST. LOUIS,
MISSOURI.

DESIGN FOR AN EYE.

SPECIFICATION forming part of Design No. 31,132, dated July 4, 1899.

Application filed June 8, 1899. Serial No. 719,851. Term of patent 14 years.

To all whom it may concern:

Be it known that I, WILLIAM G. TEMPLETON, of the city of Colorado Springs, El Paso county, State of Colorado, have invented a new and original Design for an Eye, of which the following is a full, clear, and exact description, reference being had to the accompanying drawings, forming a part hereof.

Figure 1 is a plan view of an eye embodying my new design. Fig. 2 is a front elevation of the eye, and Fig. 3 is a view in perspective of the eye.

As seen in the drawings, the leading or material feature of my design consists of an eye composed of a single length of material, the ends of which length of material are bent into the eyes 1, and in the exact center of the

length of material forming the eye, or directly opposite the point between the eyes 1, is formed a flat widened portion 2, the same being slightly wider and less in thickness than the material of which the eye is formed, and the body portions of the eye are bent rearwardly from the ends of this flattened portion to the eyes 1.

25

I claim—

The design for an eye, substantially as herein shown and described.

In testimony whereof I affix my signature in presence of two witnesses.

WILLIAM G. TEMPLETON.

Witnesses:

EDWARD E. LONGAN,
WM. J. BRASFIELD.
